[57] **ABSTRACT**

In a labeling machine including a magazine from which labels are dispensed for labeling, means for delivering a stack of said labels from a position of readiness to said magazine, and means for advancing said stack from a stand-by position to said position of readiness, the improvement which comprises a container for each stack of labels in said stand-by position said container having opposite ends and being provided at least at its end facing said magazine with separable areas, whereby upon actuation of said means for delivering said stack from said position of readiness to said magazine said separable areas separate to permit delivery of said stack of labels while said container stays in said position of readiness.

LABELING MACHINE WITH CONTAINER FOR TRANSPORT OF STACKED LABELS

The invention relates to a transport and reloading container to accommodate a stack of labels which is moved from a position of readiness into the label magazine of a labeling machine. In particular the invention relates to a transport and reloading container suitable for the automatic reloading of the label magazine of a labeling machine.

To facilitate the operation of modern high-output labeling machines automatic apparatus have been developed which assure an uninterrupted delivery of the labels to the point at which they are taken out and hence an uninterrupted operation of the labeling machine. In these apparatus a stack of labels placed in a position of readiness is pushed out of this position of readiness into the emptying label magazine of the labeling machine. Essential to such operation is the automatic moving of the label stacks into the position of readiness in step with the sequence of operations; this is accomplished in the prior-art apparatus by means of a periodically revolving conveyor means which is equipped with cells to accommodate the label stacks and with a device for pushing the label stacks out.

In these apparatus, however, the handling of the label stacks presents difficulties due to the fact that the stacks are usually tied together by means of a strip and are delivered individually wrapped. Therefore, after unwrapping the label stack the operator must remove the strip that holds it together, so that the danger exists that the stack of labels may fall apart upon insertion into the cells of the conveyor means.

The invention is addressed to the problem of devising an easy-to-handle label package in the form of a transport and reloading container for label stacks which will satisfy the special requirements of the operation of automatic label feeding systems in high-output labeling machines.

This problem is solved by suitable modification of a labeling machine including a magazine from which labels are dispensed for labeling, means for delivering a stack of said labels from a position of readiness to said magazine, and means for advancing said stack from a stand-by position to said position of readiness. In accordance with the invention there is provided a container for each stack of labels in said stand-by position, said container having opposite ends and being provided at least at its end facing said magazine with separable areas, whereby upon actuation of said means for delivering said stack from said position of readiness to said magazine said separable areas separate to permit delivery of said stack of labels which said while stays in said position of readiness. One of the ends of the container may be divided into separable individual areas while the other end is provided with an opening.

In accordance with the invention the separable individual areas of one or both ends may be integral and joined along a weakened score line in the form of a perforation or the like, or else the separable areas of one or both ends may be joined together by a mechanical locking in the form of interlocking tabs or the like.

Another feature in accordance with the invention resides in the fact that the portions of the container ends which are articulated to the sides of the container serve in the separated state, i.e., during the ejection of the label stack, as a guiding aid between the container and

the label magazine. To assure that the transport and reloading container remains in position during the ejection of the labels, holding edges are provided on the ends of the container outside of the area covered by the labels.

The advantage achieved with the invention lies primarily in the easy handling, which is due to the fact that the operator can insert the label stack into the feeding device in the form in which it is delivered, without further preparation. Another advantage is to be seen in the fact that the procedure of wrapping relatively short stacks of labels is eliminated and accordingly longer stacks of labels may be used.

The subject matter of the invention is described hereinafter with reference to the accompanying drawing wherein:

FIG. 1 is a diagrammatic plan view of an automatic apparatus for reloading the label magazine of a bottle labeling machine;

FIG. 2 shows a transport and reloading container, in closed state, for loop labels for the necks of bottles;

FIG. 3 shows the container represented in FIG. 2 in the opening state;

FIG. 4 shows a further embodiment of the container in initial condition;

FIG. 5 is a view of the container of FIG. 4 in the opening state; and

FIG. 6 shows the end of a transport and reloading container for back labels for containers.

As seen in FIG. 1, the apparatus for refilling the label magazine 1 feeding a labeling machine which is not shown consists of a cyclically advancing conveyor means 2 in the form of a rotating table which is provided with cells 3 to accommodate the transport and reloading containers 5 containing the label stacks 4.

A plunger 6, preferably hydraulically operated in step with the reloading action, pushes the label stack 4 out of its position of readiness into the label magazine 1, leaving the container 5 in cell 3.

The transport and reloading container 5 accommodating the label stack 4 is preferably constructed as a folding box which partially or wholly envelops the label stack 4. In the case of the embodiments represented in FIGS. 2, 3 and 6, the end walls of the container 5 are divided by means of lines of perforations 7 into separable individual areas or flaps 8 and 9. These individual areas 8 and 9, articulated to the sides of container 5, separate, as indicated in FIG. 3, under the pressure of the label stack 4 being pushed by the plunger 6 and serve in their end position as a transfer aid between the container 5 and the label magazine 1.

In the embodiment represented in FIGS. 4 and 5, the separable individual areas 10, 11, are joined to one another by a mechanical locking means 13 in the form of an interlocking closure which is also unfastened by the pressure of the ejected label stack 4. The arrangement may in all cases be made such that the end of the container 5 facing the plunger 6 is not divided into separable individual areas but is provided with an opening whose shape and size permits the plunger to pass through it to eject the label stack.

In the ends of container 5 there are furthermore provided holding edges 14 located outside of the label areas. These holding edges 14 will abut against stops which are fastened to the conveyor means 2 or to the cells 3, and which are not shown in the drawing, these

stops assuring that container 5 will remain in cell 3 while the label stack 4 is being ejected.

It will be appreciated that the instant specification and examples are set forth by the way of illustration and not limitation, and that various modifications and changes may be made without departing from the spirit and scope of the present invention.

What is claimed is:

1. In a labeling machine including a magazine from which labels are dispensed for labeling, a stack of labels, means for delivering said stack of labels from a position of readiness to said magazine, and means for advancing said stack from a stand-by position to said position of readiness, the improvement which comprises a container for each stack of labels in said stand-by position, said container in part having the same shape as said label stack, having opposite ends and being provided at least at its end facing said magazine with separable end flaps, whereby upon actuation of said means for delivering said stack from said position of readiness to said magazine said separable flaps separate to permit delivery of said stack of labels which stack leaves said container while said container stays in said position of readiness, said similar shapes providing sliding guided contact of said stack relative to said container.

30

2. A labeling machine according to claim 1, wherein said container is open at its end opposite that having said separable flaps.

3. A labeling machine according to claim 1, wherein 5 said separable flaps are integral with one another, the joinder therebetween being weakened.

4. A labeling machine according to claim 1, wherein said separable flaps separably interlock with one another.

10 5. A labeling machine according to claim 1, said container including a pair of longitudinal sides which at their front edges are respectively articulated to the separable flaps, said flaps when separated serving as transfer aid for the stack in moving from the container to the magazine.

15 6. A labeling machine according to claim 1, including abutment means on said magazine or in said position of readiness, said container including holding means at its end facing said magazine outside of the path of the labels in moving from said container to said magazine, whereby upon movement of said labels into said magazine said holding means engages said abutment means so that said container remains in said position of readiness.
